UNITED STATES PATENT OFFICE.

JOHN MOHN, OF DETRICK, MICHIGAN.

SIPHON STARTER AND AUTOMATIC SHUT-OFF.

Application filed April 28, 1924. Serial No. 709,375.

This invention relates to a siphon starter and automatic shut off, and my invention aims to provide a pump adapted to raise liquid for continuous flow, and shut off the flow of liquid from the supply receptacle incident to changing from one receiving receptacle to another. The pump includes a novel arrangement of a cylinder, tubular piston rod and piston, each reciprocable relative to one another, with the piston serving as a valvular means for controlling the discharge of liquid by the pump.

A siphon starter in accordance with this invention may be advantageously used when racking off beverages, that is, filling small containers from a large vessel, and as a further instance I may mention the transfer of fuel from an automobile tank to a carburetor or other tank. In fact my pump may be used in places where a siphonic action is required for the transfer of liquid, and by embodying the valvular feature in the pump, the transfer and control of liquid may be expeditiously and economically performed.

The liquid transferring means will be hereinafter specifically described and then claimed, and reference will now be had to the drawing, wherein—

Figure 1 is a longitudinal sectional view of the siphon starter showing it in position to establish communication between a supply receptacle and a receiving receptacle, and

Fig. 2 is an enlarged longitudinal sectional view of the siphon starter showing the piston thereof serving as a valve to temporarily shut off the flow of liquid.

In the drawing, 1 denotes a supply receptacle, as a barrel having its head provided with an opening 3 and extending through said opening in proximity to the bottom of the barrel is a flexible conduit 4. The liquid within the receptacle 1 is adapted to be withdrawn through the conduit 4 and placed in a receiving receptacle 5, for instance a bottle. To start the liquid flowing through the conduit 4 I provide a novel pump to induce a siphonic action, and the pump is also designed so that the flow of liquid may be temporarily shut off, without necessarily destroying the siphonic action, so that an empty receptacle may be substituted for a filled receptacle.

The pump comprises a cylinder 6 having a fixed end cap 7 provided with a nipple

8 over which may be fitted the end of the conduit 4. The opposite end of the cylinder 6 is provided with a detachable cap 9 having a tubular guide 10 for a tubular or hollow piston rod 11, which has its outer end provided with the head or peripheral flange 12 and a discharge nipple 13. The head 12 may support the pump on the mouth of the receptacle 5 with the discharge nipple 14 extending into the neck of the receptacle, and with the head 12 simply resting on the receptacle mouth, without being sealed, air may escape from the receptacle 5 as it is filled with liquid.

The inner end of the tubular piston rod 11 is reduced and formed with an annular shoulder 14, and mounted on the inner end of the piston rod is an abutment 15, preferably in the form of a screw, and a resilient seat member 16. The tubular piston rod 11 has a lateral port 17 in proximity to the seat member 16 adapted to establish communication between the cylinder 6 and the tubular piston rod 11.

Shiftable on the reduced end of the tubular piston rod 11 and adapted to engage either the shoulder 14 or the seat member 16, as a piston, comprising a flanged sleeve 18 provided with a cupped piston ring 19, a packing ring 20 and a retaining ring 21, said packing ring retaining the piston ring against the walls of the cylinder 6, and the retaining ring 21 holding the parts assembled on the sleeve 18. The sleeve 18 serves the function of a valve when in engagement with the seat member 16, because it closes the port 17.

By rapidly reciprocating the cylinder 6, on the tubular piston rod 11, the liquid in the receptacle 1 can be lifted to flow through the conduit 4 into the upper end of the cylinder 6 and through the port 17 and the tubular piston rod 11 into the receiving receptacle 5. When the cylinder 6 is raised, as shown in Fig. 2, the port 17 can be closed to maintain a head of liquid in the conduit 4, while the pump is being transferred from a filled receptacle to an empty receptacle. There is always a sufficient head of liquid in the conduit 4 to continue the siphonic action when the cylinder 6 is open to the port 17, and by embodying the valve in the pump, it obviates squeezing the conduit 4 or using any other valvular means to temporarily shut off the flow of liquid.

It is obvious that my pump may be ad-

vantageously used when making home made beverages and bottling the same, and while in the drawing there is illustrated a preferred embodiment of my invention, it is to be understood that the structural elements are susceptible to such variations and modifications as fall within the scope of the appended claim.

What I claim is:—

10. A siphon starter and automatic shut off comprising a tubular piston rod having a discharge nipple adapted to extend into a receiving receptacle and a flange adjacent said nipple adapted for supporting said piston rod relative to the receiving receptacle, said piston rod having its upper end reduced to form a shoulder, an abutment carried by the upper end of said piston rod in opposed relation to the shoulder

of said rod, said piston rod having a lateral opening adjacent said abutment, a piston reciprocable on the reduced upper end of said piston rod and limited in its reciprocation by said shoulder and said abutment, said piston closing the lateral opening of said piston rod when engaging said abutment, and a cylinder reciprocable on the lower end of said piston rod and adapted to shift said piston, said cylinder having its lower end adapted to abut the flange of said piston rod, the upper end of said cylinder adapted to communicate with a supply receptacle and afford an unobstructed chamber for the upper end of said piston rod.

In testimony whereof I affix my signature.

JOHN MOHN.
